THERMIONIC VALVES

Vaman Shantaram Bawdekar, London, England, assignor to Associated Electrical Industries Limited, London, England, a British company

Filed Apr. 25, 1960, Ser. No. 24,547

Claims priority, application Great Britain Apr. 28, 1959
3 Claims. (Cl. 313—174)

This invention relates to thermionic valves of the kind having a cathode lead extending through the upper end of the valve envelope.

The invention has an important application in valves designed for use as efficiency diodes in television receivers. Such valves have in the past been subject to noise, the source of which has been difficult to trace. In such valves the potential of the cathode varies between fairly wide limits and is subjected to large voltage pulses. It is, therefore, necessary to provide, between the cathode and heater, insulation which will stand an appreciably higher voltage than that normally used in thermionic valves.

It is also common practice with such valves to pass the cathode lead-in wire through the upper end of the valve envelope. During the gettering, deposition occurs on the internal surface of the upper part of the envelope and it has been found that in practice, during operation of the valve, there is a tendency for sparking to occur between the cathode lead and the getter deposit during the occurrence of the high voltage pulses and this sparking has been found to cause the noise above referred to. It is thought that this sparking is due to the fact that the getter film assumes a potential lying intermediate between that of the cathode and the anode and hence there will be appreciable potential differences between the cathode and the getter deposit during the pulses. This arcing limits the maximum voltage at which such a valve can be operated.

The main object of the invention is to provide an improved construction enabling such valves to be run at higher voltages.

According to the present invention a valve of the kind referred to is provided with an electrical connection between the surface of the envelope on which getter deposition occurs and a point of low potential.

It will be appreciated that the getter deposit has a degree of conductivity so that the connection need only be made to a localised area.

Preferably an electrical connection is made between the getter deposit and the cathode lead.

It has been found that such a connection appreciably reduces the tendency for sparking to occur and hence reduces the noise generated in the valve.

In order that the invention may be more clearly understood reference will now be made to the accompanying drawing which shows an example of a valve embodying the invention.

In the drawing the reference 1 indicates a valve envelope, 2 is the top mica disc supporting the upper end of the electrodes of which 3 is the anode and 4 the cathode having an insulated heater 5 within it. Above the disc 2 is a getter ring 6 and between the getter ring 6 and the disc 2 is a screen 7 to prevent getter deposition reaching the electrodes.

Extending upward from the cathode is a conductor strip 8 and to this in turn is connected a lead-in wire 9 extending through the upper end of the envelope. The getter deposition, which is indicated by the reference 10, occurs around the upper part of the envelope

2

and in accordance with the invention a conductor 11 is connected with the upper end of the strip 8 and abuts against the internal surface of the envelope so as to provide electrical connection between the getter deposition and the strip 8.

Preferably the conductor 11 is resilient and is connected to the strip 8 and lead-in wire 9 by welding at its mid point. With such a construction the valve may be assembled by pushing the electrode assembly upwards into the envelope. This will cause the conductor 11 to press against the sides of the envelope and to bow, the bowing increasing the contact area by causing the wire to lie along the inside face of the envelope. The conductor 11 can, of course, be a wire of circular cross section or a strip.

Clearly the conductor 11 is only one way of carrying out the invention.

Whilst the embodiment shown is the preferred way of carrying out the invention clearly it may be modified, or instance, the conductor 11 could be attached to the wire 9 at a higher position provided it lies along the inside of the envelope. It may either be a wire or a strip. Instead of being connected to the cathode lead, the conductor 11 could be connected to any other lead extending from the electrode assembly with a similar potential waveform to that of the top connection.

What I claim is:

1. A thermionic valve comprising an envelope, an electrode assembly located in said envelope, said electrode assembly including at least an anode and a cathode, a cathode lead extending through the end of said envelope, a gettering electrode located between the electrode assembly and the cathode lead end of said envelope, and a grounding lead for the getter deposit extending between a point of low potential and that part of the inner face of the envelope between the gettering electrode and said cathode lead end of the envelope on which part the getter deposit is formed.

2. A thermionic valve comprising an envelope, an electrode assembly located in said envelope, said electrode assembly including at least an anode and a cathode, a cathode lead extending through the end of said envelope, a gettering electrode located between the electrode assembly and the cathode lead end of said envelope and a grounding connection for the getter deposit extending between the cathode lead and that part of the inner face of the envelope between the gettering electrode and said cathode lead end of the envelope on which part the getter deposit is formed.

3. A thermionic valve comprising an envelope, an electrode assembly located in said envelope, said electrode assembly including at least an anode and a cathode, a cathode lead extending through the end of said envelope, a gettering electrode located between the electrode assembly and the cathode lead end of said envelope and a grounding connection for the getter deposit extending between the cathode lead and that part of the inner face of the envelope between the gettering electrode and said cathode lead end of the envelope on which part the getter deposit is formed, said grounding lead comprising a resilient strip extending transversely across the cathode lead to which it is attached at its mid point so that the ends are pressed resiliently against the inner face of the envelope.
